(57) **CLAIM**

We claim the ornamental design for a game piece, as shown and described.

DESCRIPTION

FIG. 1 is a perspective view of the game piece, showing our invention;

FIG. 2 is a front view thereof;

FIG. 3 is a right side view thereof;

FIG. 4 is a left side view thereof;

FIG. 5 is a back view thereof;

FIG. 6 is a top view thereof; and,

FIG. 7 is a bottom view thereof.

The broken line showing of the number on the game piece is for illustrative purposes only, and forms no part of the claimed design.
